UNITED STATES PATENT OFFICE.

THOMAS A. WAGGETT, OF EAST MOLINE, ILLINOIS, ASSIGNOR, BY MESME ASSIGNMENTS, TO TROY LAUNDRY MACHINERY COMPANY, INC., OF DOVER, DELAWARE, A CORPORATION OF DELAWARE.

PLATE PUNCHING AND FINISHING MEANS.

Application filed July 29, 1926. Serial No. 125,707.

The present invention relates to plate punching and finishing means.

More particularly the present invention relates to means for punching a plurality of 5 holes in a plate and reaming the material around said holes to remove the rough edges left by the punching tools.

An object of the present invention is to provide mechanism of the kind referred to 10 in which the punching and reaming operations are performed in timed relationship with one another.

A further object is to provide a plate punching and reaming machine which will 15 expeditiously handle plates in which a large number of holes are to be punched and reamed.

A further object is to provide a machine for punching and reaming holes in a plate 20 which is simple, positive in action and well adapted to meet the requirements of commercial service.

Further objects will appear as the description proceeds.

25 Referring to the drawings—

Figure 1 is a top plan view of one embodiment of the present invention;

Figure 2 is a view in front elevation of the structure shown in Figure 1;

30 Figure 3 is a fragmentary view showing, on an enlarged scale, an end view of the structure shown in Figures 1 and 2;

Figure 4 is a fragmentary view, on an enlarged scale, illustrating the means for communicating a step-by-step movement to the plate to be operated upon;

Figure 5 is a sectional view taken along the plane indicated by the arrows 5—5 of Figure 1;

40 Figure 6 is a sectional view, on an enlarged scale, illustrating a preferred embodiment of the reamer structure, said figure being taken along the plane indicated by the arrows 6—6 of Figure 1;

45 Figure 7 is a fragmentary view taken along the plane indicated by the arrows 7—7 of Figure 2;

Figure 8 is a perspective view illustrating the cooperative relationship between the 50 punching die and the reaming mechanism; and

Figure 9 is a perspective view illustrating the mechanism for producing a step-by-step movement of the plate to be operated upon.

The present invention is particularly useful in punching and reaming the holes in plates designed for forming the cylindrical walls of washing machine cylinders. Such plates are provided with a large number of holes for permitting the ingress and egress of washing medium while retaining the goods to be washed. According to the present invention, a flat plate to be operated upon is clamped in position and punches are operated to punch one or more rows of holes at a single operation. The punching operation ordinarily leaves a burr, and the present invention contemplates reaming means operated in predetermined relationship with the punching means for removing the burr from the various holes left from such a punching operation. The plate to be operated upon is fed through the machine with a step-by-step movement, the holes being punched one or more rows at a time and being advanced into position to be operated upon by the reamers.

Referring first to Figure 1, the numeral 10 indicates the bottom die of a punch, the upper or movable die being omitted from 80 said figure for purposes of clarity. The numerals 11—11 indicate a pair of guideways adapted to slidably receive a pair of plate clamping members 12—12. As illustrated in Figure 5, each of the plate clamping members 12 is provided with a recess 13 adapted to receive the side edge of a plate 14. The cap screw 15 is provided for firmly gripping the adjacent side edge of the plate 14. Each of the plate clamping members 12 is provided on its under side with the removable rack 16, which rack forms part of the step-by-step mechanism by means of 85 which the plate 14 may be advanced with a step-by-step movement through the machine.

By reference to Figure 3 it will be noted that the punches 17—17 carried by the block 18 are disposed in position to cooperate with the stationary die 10. Said block 18 is carried by the operating member 19, which may be driven from any preferred source of power (not shown). Also carried by the operating member 19 is the depending support arm 20, which carried the removable camming bar 21. Said camming bar 21 is provided near its lower extremity with the camming surface 22 adapted to cooperate with the abutment 23 carried by the reciprocating

plate 24 (Figure 9). Said reciprocating plate 24 is urged in a right-hand direction as the parts are viewed in Figures 4 and 9 by the spring 25. Pivotally mounted upon said plate 24 is the dog or pawl 26, which is weighted by means of the ball 27 to normally occupy a position in engagement with the rack 16. It will be obvious from an inspection of Figure 9 that an upward movement of the camming bar 21, which is to say an upward movement of the operating member 19, will move the plate 24 in a left-hand direction as the parts are viewed in Figures 4 and 9, whereby the dog or pawl 26 will move the cooperating rack 16 one step toward the left. As the operating member 19 and the camming bar 21 descend, the camming surface 22 of the camming bar 21 will be moved out of engagement with the abutment 23, and the spring 25 will retract the plate 24 to allow the pawl or dog 26 to move into engagement with the next successive tooth of the rack 16.

Also mounted upon the operating member 19 are the pair of depending bars 28-28, which depending bars 28-28 have the function of moving the reaming mechanism to reaming position through mechanism which will now be described.

The numeral 29 indicates a reamer block provided with a plurality of spindles 30-30. Each of said spindles 30-30 is provided at its lower extremity with the gear 31. As indicated in Figure 1, the spindles 30-30 are arranged in two parallel rows. The gears 31 at the lower extremities of the spindles in each row are connected in a train in the manner indicated in Figure 7, being driven by the common gear 32. Said gear 32 is driven by the gear 33. The gears 31-31 and gear 32 move up and down with the block 29. The gear 32 is driven by the gear 33, which according to the illustrated embodiment of the present invention does not have an axial movement. In order to permit movement of gears 30-31 and gear 32 relative to gear 33, said gear 33 is made relatively wide, in order to avoid the demeshing of gear 32 from gear 33. The gear 33 may be driven by the gear 34, which gear 34 may be driven by the pulley 35.

Each of the spindles 30 is provided at its upper extremity with a reaming tool 36. In order to permit the ready insertion and withdrawal of the reaming tools 36, each of said tools 36 is provided with a shank 37 having an annular groove 38 adapted to receive the spring-pressed ball 39. It will be obvious that, by means of the construction illustrated, each of the reaming tools 36-36 is removably held within its corresponding spindle 30. The lower extremity of each of the spindles 37 may be non-circular in cross section, fitting into a smaller hole in the spindle 30, whereby rotary movement of the

spindles 30 will be communicated to the reaming tools 36.

From an inspection of Figure 8 it will be noted that the reamer block 29 is pivotally supported by means of the yoke 40, which yoke is pivoted upon the relatively fixed lugs 41-41. The bars 28-28 are positioned to engage with the yoke 40 when the operating member 19 is depressed. Lowering of the operating member 19 will therefore not only accomplish the punching operation by the punches 17-17, but will cause the rocking of the yoke 40 to lift the reamer block 29. The result will therefore be accomplished that a row or rows of holes will be punched, and at substantially the same time a row or rows of holes previously punched will be reamed.

The numeral 42 indicates a lever pivoted for movement about the pivot 43, which lever 42 is connected by means of the link 44 to the middle of the yoke 40. By depressing the free extremity of the lever 41, the operative may lift the block 29 independently of the operating member 19, thereby accomplishing a reaming operation entirely independently of the punching operation, if such a reaming operation should be considered to be necessary.

The mode of operation of the above described embodiment of the present invention will be clear without detailed explanation. It may be stated briefly, however, that when it is desired to punch and ream a plurality of holes in a plate, said plate will be clamped with its side edges disposed within the clamping members 12-12 at the two sides of the machine. When said plate has been properly positioned for the first punching operation, the operating member 19 will be lowered through mechanism not shown, whereby the punches 17-17 in cooperation with the die member 10 will punch a plurality of holes. When the operating member 19 is in its lower or punching position, the camming surface 22 of the camming bar 21 will of course be in lowered position, whereby the spring 25 may draw the abutment 23 to the right as the parts are viewed in Figures 3, 4 and 9, permitting the pawl or dog 26 to engage with the next successive tooth on each of the racks 16. When the operating member 19 is again raised, the camming surface 22 will move the abutment 23, plate 24 and pawl or dog 26 to the left as the parts are viewed in Figures 3, 4 and 9, resulting in movement of the plate 14 toward the left. After one or more punching operations have been performed, holes previously punched in the plate 14 will be positioned over the reaming tools 36-36. Each time the operating member 19 is depressed, the operating bars 28-28 thereof will engage the yoke 40 to cause the lifting of the reamer block 29.

Inasmuch as the reaming tools 36-36 are be-

ing continuously rotated, the result will be accomplished that at each downward movement of the operating member 19, not only will a punching operation be performed, but 5 the reamer block 29 will be raised to perform reaming functions on holes previously punched.

Though a preferred embodiment of the present invention has been described in detail, it will be clear that many modifications 10 will occur to those skilled in the art. It is intended to cover all such modifications that fall within the scope of the appended claim.

What is claimed is:

15 In punching and reaming mechanism, in combination, plate holding means, means for

advancing said holding means with a step-by-step motion, punching means, a reamer block carrying a plurality of reamers, means for rotating said reamers, means for pivotally mounting said reamer block, means operating in synchronism with said punching means for moving said reamer block to bring said reamers into operative relationship with holes previously punched by said punching means, and means for moving said reamer block into operative position independently of said punching means. 20 25

Signed at East Moline, Illinois, this 26th day of July, 1926.

THOMAS A. WAGGETT.
